CLAIM

The ornamental design for sunglasses, as shown and described.

DESCRIPTION

FIG. 1 is a front perspective view of the sunglasses of the present invention showing my new design;

FIG. 2 is a front side elevational view thereof;

FIG. 3 is a back side elevational view thereof;

FIG. 4 is a side elevational view thereof;

FIG. 5 is another side elevational view thereof;

FIG. 6 is a top plan view thereof;

FIG. 7 is a bottom plan view thereof;

FIG. 8 is a front perspective view of the sunglasses in a folded position;

FIG. 9 is a back side elevational view of FIG. 8; and,

FIG. 10 is a top plan view of FIG. 8.

The elements shown in broken lines are for illustrative purposes only and form no part of the claimed design.
